C. H. KREBS

SAFETY RAZOR

Filed Feb. 3, 1921

INVENTOR.

CHARLES H. KREBS

CHARLES H. KREBS
Ira M. Jones.
ATTORNEY.

UNITED STATES PATENT OFFICE.

CHARLES H. KREBS, OF MILWAUKEE, WISCONSIN, ASSIGNOR TO KREBS SAFETY RAZOR CORPORATION, OF CHICAGO, ILLINOIS, A CORPORATION OF ILLINOIS.

SAFETY RAZOR.

Application filed February 3, 1921. Serial No. 442,112.

To all whom it may concern:

Be it known that I, CHARLES H. KREBS, a citizen of the United States, and resident of Milwaukee, in the county of Milwaukee and State of Wisconsin, have invented certain new and useful Improvements in Safety Razors; and I do hereby declare that the following is a full, clear, and exact description thereof.

10 My invention relates to new and useful improvements in safety razors and in the detachable blades for use therewith.

It is the primary object of this invention to provide a simply constructed razor of this character which as the result of its few number of parts, can be inexpensively manufactured and will be quite light in weight, this being particularly true of the head.

An additional object of the invention is 20 to provide a safety razor head of relatively small size which will take a small blade, the result being that such a razor as this can be used in all restricted places, for instance close beneath the nose, where it is impossible to employ a large razor to any advantage. In this connection it is also an object to dispose the plane of the blade at approximately 45° to the center line of the handle.

30 A further important object of the invention is to provide a blade seating head having a resilient sheet metal blade holder permanently secured thereto which, by its spring action will effectively retain a blade in place, while allowing it to be readily removed when necessary.

It is likewise an important object of this invention to provide a razor of this character which has an entirely open space between the guard and blade-supporting head, thereby allowing these parts to be easily cleansed of lather and the like.

40 Still another object of the invention is to provide a combined blade-supporting head and guard which can be stamped from a single piece of sheet metal.

A further important object of the invention is to provide a detachable safety razor blade having attaching means to each on its 50 opposite ends.

With these objects in view the invention resides in the novel features of construction, combination and arrangement of parts which will be hereinafter more particularly

described and claimed, and shown in the accompanying drawing wherein:

Figure 1 represents a side elevational view of a safety razor constructed in accordance with the invention, the blade being omitted;

Figure 2 is an end elevational view showing more particularly the head and blade retaining means;

Figure 3 is a substantially central sectional view taken transversely of the head;

Figure 4 is another end elevational view looking from a somewhat different angle from the view shown in Figure 2;

Figure 5 is a plan view of the blade for use in this razor;

Figure 6 is a view similar to Figure 3 of a slightly modified form of my invention, and

Figure 7 is an end elevational view similar to Figure 4 of that form of my invention depicted in Figure 6.

Referring more particularly to the accompanying drawing, it will be seen that my invention comprises, in its preferred embodiment, a handle 1 having an attaching shank 2, and means carried by the shank for supporting a blade 3. The main portion of this blade-supporting means consists of a head 4 formed from an angular plate having an attaching flange 5 and a blade engaging flange or bed 6, the first mentioned flange being secured to said shank 2 in a suitable manner. As indicated in Figure 1 the blade seating surface of the bed 6 is in a plane substantially at an angle of 45° with a plane containing the axis of the handle 1.

The free edge of the flange of the head 4 forming the bed 6 has a guard 7 formed integrally therewith and the same includes a plurality of guard teeth 8 and connecting legs 9. One of these legs 9 is disposed at each end of the guard and serves to connect the same with the bed 6. As shown in Figures 1 and 3, the teeth 8 of the guard intersect the plane of the face of the bed 6 approximately at right angles and their free ends are spaced from the adjacent edge of said bed the distance that the blade 3 projects beyond the latter.

In that form of my invention, illustrated in Figures 1 to 5, the back 10 of the guard connecting the legs 9 is a strip which is

folded upon itself longitudinally of its length as indicated at 11 whereby to provide a re-enforcement. The bent over portion of the back obviously may be disposed inwardly or outwardly of the guard as indicated in Figures 1 and 3, or extended at right angles to the teeth and the other portion of the back. Obviously such a re-enforcement provides considerable strength and rigidity and insures the guard being maintained in perfect alignment with the cutting edge of the blade.

The blade holder for the blade 3 consists of a resilient sheet metal plate 12 of light gauge and having considerable natural spring action, the same having an attaching flange 13 which overlies the attaching portion 5 of the head and is permanently secured thereto as by the rivets 14. The blade engaging flange 15 of the blade holder overlies the bed 6 and is curved in such a manner that its free edge is turned in toward and engages the free edge of said bed except when a blade is in place, under which conditions the latter is firmly pressed against the former. In addition to this contact between the edge of the spring blade holder and the blade, the latter is held in contact with the bed 6 at its inner edge as shown in Figure 3. The opposite free corners of the blade-engaging flange 15 are provided with lips 16 and 17 respectively, and the end thereof adjacent said lip 16 has a notch 18. Furthermore the lip 16 has its outer end curved as at 19 and its inner end sharply cut at a right angle to the free edge of the flange 15 as at 20, the other lip 17 also having its inner side curved as will be seen at 21 in Figure 2.

The blade 3 which is to be retained in position by this spring blade-holder 12 is an elongated metal strip having one edge sharpened and provided at one end adjacent the non-sharpened or back edge with a locking lug 22. This lug projects from this end edge longitudinally of the blade, and occupying the same relative position at the other end is a finger-piece 23. In addition to projecting beyond the end of the blade, this finger-piece 23 is also defined by a kerf 24 which is cut in said end parallel to and midway the longitudinal edges of the blade.

In inserting the blade in the holder, the locking lug 22 is inserted between the bed 6 and the blade-engaging flange 15 at the notched end of the latter, said notch aiding the lug in entering between these parts. Upon insertion of the end of the blade containing said locking lug, the blade is pushed longitudinally of the head until said lug projects beyond the opposite end of the blade-engaging flange to that in which the notch is formed, whereupon movement is stopped by the blade end striking a stop finger 25. This finger is bent laterally from

one end of the bed-plate as shown in Fig. 1, thus defining a space between it and the attaching portion of the blade-holder 12, this space being occupied by said locking lug 22. Upon positioning of the locking lug in this space, the lip 16 springs into the kerf 24 and thus holds the other end of the blade from movement in either direction.

In order to facilitate insertion of the locking lug between the bed 6 and blade-engaging flange 15, the former is provided adjacent the notch 18 with a projecting blade-rest 26, and the curved parts 19 and 21 of the lips 16 and 17 respectively greatly facilitate the movement of the blade when it is being inserted. The straight cut side 20 of the lip 16, however, engages with the end of the kerf 24 and effectively locks this end of the blade against longitudinal or forward shifting. Furthermore the edge of the flange 15 between the lips 16 and 17 engages the blade substantially throughout its length and thus further aids in retaining the same in position.

In Figures 6 and 7 I have illustrated a slightly modified form of my invention in which the bend 9 is eliminated and the outer free longitudinal edge of the bed 6 is curved rearwardly, as at 27 which provides means for re-enforcing the blade holder and also a guard for the cutting edge of blade 3. As in that form of my invention depicted in Figures 1 to 5 the bed 6 has its medial portion cut away in order that the entire blade surface may be clear to prevent the clogging of the same by the cut hairs and lather. The curved longitudinal edge of the bed is provided with teeth 28, similar to teeth 8 and the cutting edge of the blade is preferably positioned inwardly of the inner ends thereof as best shown in Figure 6. The side edges of the blade 3 rest upon the end strips 29 of the bed 6 to form a firm support therefor and the corners of the blade at each end of the cutting edge thereof are preferably slightly rounded to eliminate any possible danger of the user accidentally cutting himself thereon.

I claim:

1. In a safety razor, a blade-seating head, a guard carried thereby, a resilient blade-holder secured along one longitudinal edge portion to the head, the other longitudinal edge portion being free and urged toward the head whereby to define a blade-receiving space between the seating surface of the head and the inner surface of the blade-holder, a pair of spaced lips on said free edge of the blade-holder, the outer end of one lip and the inner end of the other being rounded, means facilitating the insertion of a blade into said space from one end, and a stop finger at the opposite end of the space and partially closing the same, said space being adapted to receive a blade having a

locking lug on one end and a kerf in the other end, the lug being disposed in the partially closed end of said space adjacent the stop finger, the kerf having the first mentioned lip engaged therein.

2. In a razor, a blade seating head, a resilient blade holder rigidly secured along the rear longitudinal edge portion of the head, the other longitudinal edge portion 10 being free and urged toward the head whereby to define a blade receiving recess between the seating surface of the head and the inner surface of the blade holder, a blade insertable between the head and blade holder 15 with its front cutting edge aligned with respect to the other longitudinal edge of the head by the rear longitudinal edge of the

blade engaging the rear portion of the blade holder throughout substantially its entire length, a stop finger at one end of the space 20 and partially closing the same, and a projection on the inner end of the blade and engageable behind said stop finger, said blade being inserted longitudinally between the blade holder and head until said projection engages behind the stop finger and said blade being removed by swinging the outer end of the blade on an arc with said projection pivoting on said stop finger.

In testimony that I claim the foregoing 30 I have hereunto set my hand at Milwaukee, in the county of Milwaukee and State of Wisconsin.

CHARLES H. KREBS.
